WRENCH AND DRILL UNIT

Ronald L. Jenny, 3556 Stoner Ave.,
Los Angeles, Calif. 90066

Filed May 29, 1973, Ser. No. 364,376

Term of patent 14 years

Int. Cl. D8—05

U.S. Cl. D8—68

FIG. 1

FIG. 2

FIG. 3

FIG. 4

FIG. 5

FIG. 1 is a perspective view of a wrench and drill unit showing my new design;

FIG. 2 is a side elevational view thereof;

FIG. 3 is a bottom plan view thereof;

FIG. 4 is a front elevational view thereof; and

FIG. 5 is a rear elevational view thereof.

I claim:

The ornamental design for a wrench and drill unit, substantially as shown.
